CLAIM

The ornamental design for a surgical clip applicator, substantially as shown and described.

DESCRIPTION

FIG. 1 is a top perspective view of a surgical clip applicator showing our new design;

FIG. 2 is a top plan view thereof;

FIG. 3 is a side elevational view thereof, looking from the bottom of FIG. 2. The other side being a mirror image thereof;

FIG. 4 is a front elevational view thereof, looking from the left in FIGS. 2 and 3.

FIG. 5 is a rear elevational view thereof, looking from the right in FIGS. 2 and 3.

FIG. 6 is a bottom plan view thereof.
